UNITED STATES PATENT OFFICE.

CHARLES C. BLAKE, OF BROOKLINE, MASSACHUSETTS.

HEEL-LASTING MACHINE.

1,386,681.

Specification of Letters Patent. Patented Aug. 9, 1921.

Application filed March 27, 1916. Serial No. 36,958.

To all whom it may concern:

Be it known that I, CHARLES C. BLAKE, a citizen of the United States, residing at Brookline, in the county of Norfolk and State of Massachusetts, have invented a new and useful Improvement in Heel-Lasting Machines, of which the following is a specification.

The present invention relates to end lasting machines and more particularly to an end lasting machine for lasting the heel seat of a Blake welt shoe.

In the wiper type of end lasting machine it has been customary to first complete the overdraw movement of the wipers and then to retract the wipers so as to expose the edge of the overdrawn upper sufficiently to permit the insertion of fastenings therethrough. As well known to those skilled in the art this retractive movement of the wipers is highly objectionable.

An object of the present invention is to produce an end lasting machine in which the objectionable retractive movement of the wipers hereinbefore referred to is obviated.

To the accomplishment of this object and such others as may hereinafter appear, the features of the present invention contemplate the provision of certain devices, combinations and arrangements of parts fully set forth hereinafter, the advantages of which will be readily understood by those skilled in the art.

The various features of the present invention will be readily understood from an inspection of the accompanying drawings illustrating the best form of the invention at present known to the inventor, in which, Figure 1 is a right side sectional elevation of the heel lasting machine with the wipers at the completion of their wiping stroke and with the driving mechanisms for driving the tacks and feeding the tacker thrown out of operation;

Fig. 2 is a front elevation;

Fig. 3 is a detail, in right side sectional elevation, of the work supporting and clamping devices;

Fig. 4 is a detail in front sectional elevation of the work supporting and clamping devices;

Fig. 5 is a detail, partly in section, of the heel lasting mechanism showing the operative position of the wipers when initially engaged with the work;

Fig. 6 is a detail elevation, partly in section, showing the wipers at the completion of their updraw movement;

Fig. 7 is a detail elevation, partly in section, showing the position of the wipers at the completion of their overdraw movement;

Fig. 8 is a plan of the wipers;

Fig. 9 is a side elevation of the wipers;

Fig. 10 is a front sectional elevation of the wiper carrier and the wipers supported thereby taken on the line 10—10, Fig. 7;

Fig. 11 is a plan of the tacker head and the devices supported therefrom;

Fig. 12 is a detail in side elevation of the tacker head showing the position of the parts when a tack is delivered to the tack-driving throat and when the gate is operated to release a tack from the raceway;

Fig. 13 is a detail in side elevation of the tacker head showing the position of the parts when the reciprocating picker is about to engage a tack released from the end of the raceway;

Fig. 14 is a detail in side elevation of the tacker head at the time the tack is driven and the gate closed;

Fig. 15 is a detail rear sectional elevation on the line 15—15, Fig. 12;

Fig. 16 is a front elevation of the tacker head;

Fig. 17 is a left side elevation of the tacker head;

Fig. 18 is a left side elevation, partly in section, of one of the cams for the tacker and the clutch for the tack-driving shaft;

Fig. 19 is a detail in left side sectional elevation of the tack nozzle and the devices for centering the tack therein;

Fig. 20 is a detail in plan, partly in section, of the slides for supporting and guiding the tacker head;

Fig. 21 is a detail in plan, partly in section, of the actuating devices for feeding the tacker;

Fig. 22 is a detail in right side elevation of the driving mechanisms for inserting tacks and feeding the tacker;

Fig. 23 is a diagrammatic plan of part of the actuating mechanism for feeding the tacker;

Fig. 24 is a front sectional elevation on the line 24—24, Fig. 21;

Fig. 25 is a front sectional elevation on the line 25—25, Fig. 22;

Fig. 26 is a right side sectional elevation on the line 26—26, Fig. 21;

Fig. 27 is a front elevation of the tack-handling mechanisms;

Fig. 28 is a right side sectional elevation of the tack-handling mechanisms;

5 Fig. 29 is a detail in front elevation of the rotating hopper;

Fig. 30 is a detail in plan of the tack-storage raceway;

Fig. 32 is a front sectional elevation on the line 32—32, Fig. 31;

Fig. 33 is a detail in plan of one of the buckets of the hopper; and

15 Fig. 34 is a rear elevation of one of the buckets of the hopper.

Referring to the drawings for a preliminary general description of the heel lasting machine the work is supported upon a horizontal table in position for the operation of wipers which are manipulated by the operative to updraw and overdraw the upper at the heel seat. At the completion of the updraw movement of the wipers the back 20 edges thereof are separated from the edge of the shoe bottom by a strip of overdrawn upper so that the overdrawn upper may be fastened without retracting the wipers. The strip of overdrawn upper is fastened 25 by an automatic tacker which is fed during its tack-inserting movement to transfer the point of operation around the heel seat from one breast corner to the other at which point the driving mechanisms for driving 30 the tacks and feeding the tacker are automatically thrown out of operation.

The machine illustrated in the drawings 40 performs the heel lasting operation on a partially lasted shoe comprising an upper 1 (Figs. 1 and 2) the forepart of which is held in lasted position against the edge of the sole on the bottom of the last by a binder 2 secured in its binding position by a clamp 3 the jaws of which are arranged to 45 embrace the opposite sides of the shoe. The upper at the shank and around the heel seat projects loosely about the shoe except at substantially the breast line where a cord extending across the shoe, connects the 50 free edges of the upper. The partially lasted shoe is mounted on a jack 4 to which a leader 5 (Figs. 3 and 4) is attached between runners 6 depending from a frame extending laterally from the jack, 55 During the operation of the machine the jack 4 is supported by a flat table 7 carried by a head 8 secured to a base 9. The jack is secured to the leader so that there is a predetermined relation between the edge 60 of the sole on the bottom of the last and the guiding flange on the leader.

In order to provide for the proper location of the jack on the table 7 to insure the proper operation of the heel lasting instrumentalities the table 7 is provided with a

slideway 10 (Fig. 3) for a slide 11 which carries a plate 12 having jaws arranged in a V to embrace the heel end of the leader. The plate 12 is normally advanced toward the front end of the table 7 by a spring 13 coiled around a rod 14 secured to the slide 11 and interposed between the back of the slide 11 and the end of a spring chamber 15 formed in the head 8. After the heel end of the leader is properly engaged with the jaws in the plate 12 the jack and plate 12 are pushed rearwardly until the leader 5 engages a fixed stop 16, on the table 7, which loosely passes through a hole 17 formed in the slide 11. The stop determines the operative position of the work with relation to the heel lasting tools.

To clamp the jack in operative position on the table 7 the machine carries a pair of arms 18 (Figs. 1, 2, 3 and 4) arranged to embrace the runners 6 and also a plate 19 having jaws arranged in a V to embrace the toe end of the leader. The arms 18 are pivoted on the head 8 beneath the table 7 (Fig. 4). The lower ends of the arms 18 are 90 connected by links 20 to the upper end of a box 21. The lower end of the box 21 is carried by a rod 22 (Fig. 3) which is adjustably connected to the free end of an arm 23 projecting from a rock shaft 24 journaled in the base 9. The rock shaft 24 is provided with a second arm 25 (Fig. 1) which is connected by a rod 26 to a treadle 27 mounted to move vertically on a pivot 28 and to move laterally about a pivot 29. With this construction depression of the treadle vertically about its pivot 28 closes the arms 18 upon the runners 6. To lock the arms 18 in clamping position the treadle is moved laterally about the pivot 29 to position the 100 treadle beneath a locking lug 30 (Figs. 1, 2 and 4) carried by the base 9.

The plate 19 which embraces the toe end of the leader is carried upon a slide 31 (Fig. 3) mounted to slide in the slideway 10. After the leader 5 is engaged with the stop 16 and before the arms 18 are engaged with the runners 6 the plate 19 is moved by hand to embrace the toe end of the leader. In order to lock the plate 19 in engagement with the toe end of the leader when the arms 18 are actuated to clamp the runners 6 the slide 31 is provided with a depending arm 32 which projects upwardly from a horizontal rod 33 mounted to slide freely in a lug 34 depending from the head 8. The rod 33 is normally loosely embraced by a clamping arm 35 pivoted to a horizontal link 36 which in turn is pivoted to a vertical arm 37 carried by a rock shaft 38 journaled in a bracket 39 on the frame 9. The rock shaft 38 is provided with a second arm 40 (Fig. 1) which is connected to the arm 25 by a link 41. With this construction the rod 33 may be freely moved through the opening in the 115 120 125 130

clamping arm 35 to position the plate 19 against the toe end of the leader. When the treadle 27 is actuated to close the arms 18 upon the runners 6 the arm 35 is cramped 5 on the rod 33 thus locking the plate 19 in position against the toe end of the leader. The rod 33 and the runners 6 are released, when the treadle is disengaged from the locking lug 30, by a coiled spring 42 (Fig. 10 3) connected at its opposite ends to the base 9 and arm 23, respectively.

In order to support the heel lasting instrumentalities the head 8 is provided with a vertical yoke 43 (Figs. 1, 5, 6 and 7) which 15 supports a cylindrical bearing 44 pivoted at 45 between the arms of the yoke. The bearing 44 loosely carries a cylindrical block 46 formed on a yoke 47. The arms of the yoke 47 extend in a direction substantially longitudinally of the shoe and terminate in a 20 bridge 48 which forms a transverse arch over the shoe bottom.

The bridge 48 supports a wiper carrier 49 having wipers 50 suspended therefrom. To 25 this end the wiper carrier 49 carries a pair of struts 51 (Fig. 10) which are universally connected at their upper ends to the wiper carrier and at their lower ends to the wipers 50. The wipers 50 comprise a pair of sections jointed at 52 (Figs. 8, 9 and 10) and each section carries a narrow spring metal finger 53 which constitutes the active faces of the wipers. In the axis of the pivot 52 the wipers are universally connected to a 35 third strut 54 (Figs. 5, 6 and 7) the upper end of which is loosely mounted in a chamber 55^a formed in the wiper carrier 49.

In order to gage the initial operative position of the wipers with relation to the shoe 40 bottom the bridge 49 carries a gage 55 (Figs. 5, 6 and 7). The sole-engaging foot of the gage 55 is swiveled on the lower end of a post 56 which is adjustable vertically in an 45 L-shaped carrier 57 pivoted centrally at 58 on the bridge 48. The gage 55 is normally held in a central position by a leaf spring 59 secured to the bridge 48 and arranged to engage the square end of the gage carrier 57. The gage 55 engages the shoe bottom under 50 the influence of a pressure mechanism. To this end the bearing 44 is pivoted to a cylindrical sleeve 60 which slides over a cylindrical arm 61 pivoted at 62 between the arms of a yoke 63. The yoke 63 is carried 55 by a rock shaft 64 journaled in the head 8. Interposed between the bottoms of the sleeve 60 and arm 61 is a spring 65 which is coiled around a rod 66 loosely passing through the sleeve 60 and arm 61 and held in place by 60 nuts 67 on the opposite ends of the rod. With this construction the sleeve 60 and arms 61 and 63 form a toggle one of the arms of which is constructed to yield longitudinally.

65 In order to position the gage 55 on the

shoe bottom and apply the pressure mechanism thereto simultaneously with the clamping of the arms 18 and plate 19 the rock shaft 64 is provided with an arm 68 (Fig. 1) which is connected to the treadle 27 by a rod 69. With this construction actuation of the treadle 27 tends to straighten the arms of the pressure toggle thus tipping the bridge 48 downwardly about the pivot 45 and thereby placing the gage 55 upon the shoe 75 bottom. Continued pressure on the treadle 27 causes the spring 65 to be compressed thus applying pressure to the gage 55. As it is desirable that the gage 55 will always become elevated from the shoe bottom when 80 the treadle 27 is released, the base 9 carries a stop 70 (Fig. 1) which engages the arm 68 during the depressing of the treadle 27 and prevents the complete making of the pressure toggle. When the treadle 27 is released 85 a spring 71 (Fig. 3) connected at one end to the pivot 62 and at the other end to the base 9 elevates the gage 55 from the shoe bottom.

The gage 55 determines the operative position of the wipers with relation to the shoe bottom. The initial operative position of the wipers as determined by the gage 55 is such that the fingers 53 engage the 90 upstanding upper just below the exposed face 95 of the shoe bottom when the wipers are closed upon the shoe by manipulation of the handles 72 connected to the wipers. This position is illustrated in Fig. 5. After the fingers are initially engaged with the upper 100 in the manner described further actuation of the handles causes the fingers 53 to slide up the back of the shoe against the pressure of the spring 65 thus imparting an updraw movement to the upper and stretching it 105 around the face of the heel. The gage 55 is elevated from the shoe bottom during this updraw movement of the wipers thus causing the pressure of the compressed spring 65 to be transmitted through the wipers to 110 the upper engaged by the fingers 53. Continued closing movement of the handles 72 causes the wipers to wipe the updrawn upper over upon the shoe bottom.

By mounting the wipers in the manner described they rock longitudinally in the bearing 44 to adapt themselves to the plane of the heel seat, move vertically about the horizontal axis 45 to updraw the upper, swing laterally about the connection with 120 the strut 54 to adapt themselves to the swing of the heel seat, and move longitudinally of the shoe about the connections with the struts 51, which also move about their connections with the wiper carrier 49, 125 to wipe the updrawn upper over the heel seat. The pivot 52 and struts 51 are mounted so that their projections upon the plane of the shoe bottom coincide with the shoe bottom between the ends thereof. Conse- 130

quently at the completion of the wiping stroke of the wipers the back or inactive edges of the wipers are separated from the edge of the shoe bottom by a strip of overdrawn upper. This construction permits the fastening of the overdrawn upper to the heel seat without the objectionable retracting movement of the wipers featured in end lasting machines of the prior art.

10 In order to secure the upper to the heel seat the machine is provided with a traveling tacker which automatically inserts tacks in the strip of overdrawn upper separating the back edges of the wipers from the edge 15 of the shoe bottom around the heel seat from one breast corner to the other. The tacks are driven into the shoe by a driver 73 (Figs. 17 and 19) which operates through a throat 74 formed in a nozzle 75 supported from a head 20 76. The driver 73 is secured by a screw 77 to a slide 78 which is weighted by a weight 79. The slide 78 reciprocates in ways 80 formed in the head 76.

To operate the driver the slide 78 is connected by a link 82 to the free end of a spring metal arm 83 the other end of which is secured to an arm 84 pivoted on a horizontal stud 85 secured to the head 76. The driver 73 is actuated to drive the tack by a 30 spring 86 which is coiled about a rod 87 pivoted on the head 76 and loosely passed through a horizontal stud 87^a on the arm 84. The spring 86 is interposed between the top of the stud 87^a and a washer 88, on the rod, 35 backed up by suitable adjusting and locking nuts 89. To compress the spring 86 for the driving stroke of the driver the arm 84 carries a shouldered stud 90 which is embraced by a slotted connecting rod 91 pivoted at 92 on a crank arm 93. The crank arm 93 is loosely pivoted on a horizontal shaft 94 journaled in the head 76. The crank arm 93 is rotated in the direction of the arrow, Fig. 17, to elevate the arm 84 40 and thus compress the spring 86 by a pin 95 carried by a disk 96, on the shaft 94, and arranged to engage the crank arm 93. The pin 95 carries the crank arm 93 and the connecting rod 91 from the full line position 45 (Fig. 17) to the dotted line position. When the crank arm 93 passes the center the compressed spring 86 is free to expand thus actuating the driver 73 to drive the tack. The crank arm 93 moves under the influence 50 of gravity ahead of the pin 95 back to its initial position to be engaged by the pin 95. The slot in the connecting rod 91 limits the driving movement of the driver 73 to the end of the nozzle 75. The spring arm 83 55 allows the lower end of the driver 73 to project out of the nozzle 75 (Fig. 19) under the influence of the momentum of the weighted slide 78, thus insuring the driving of the tack by a whipping stroke. To prevent the 60 compressed spring 86 from rotating the 65

shaft 94 in a reverse direction when the machine is stopped with the spring 86 under compression, the right side of the head 76 carries a ball clutch 97 (Fig. 18) arranged to engage the peripheral edge of a disk 98 70 (Fig. 14) on the shaft 94. The ball clutch 97 permits the shaft to rotate in the direction of the arrow Fig. 17 but clutches the disk 98 when a tendency arises to rotate the shaft 94 in the reverse direction. 75

The shaft 94 is provided with a bevel gear 99 which meshes with a similar gear 100 on the end of a horizontal shaft 101 journaled in the head 76. The shaft 101 is connected by a universal joint 102 to a sleeve 103 (Fig. 22), splined to slide freely on a short shaft 104 which is connected by a universal joint 105 to a shaft 106 journaled in bearings supported from a vertical slide 107 (Fig. 25) mounted to slide in a column 108 (Fig. 1) 80 supported by the base 9. The shaft 106 is provided with a bevel gear which meshes with a similar gear 109 loosely mounted on a vertical shaft 110 passing loosely through a three-armed bearing 111 supported from the slide 107. The bevel gear 109 is provided with clutch teeth 112 adapted to be engaged by clutch teeth formed on a clutch sleeve 113 splined on the shaft 110. The shaft 110 is driven continuously through worm gearing 90 during the operation of the machine from a horizontal shaft 114 (Fig. 2) driven by an electric motor 115 mounted on an extension of the base 9. 95

The tacks for fastening the overdrawn upper are carried in an inclined raceway 116 (Figs. 11, 12, 13, and 14) composed of a pair of spaced plates to form a roadway secured to the head 76 and having extensions 117 (Fig. 12) thereon bolted to the nozzle 75. 100 The roadway for the tacks between the plates is covered by a cover 117^a which is spaced above the plates to permit a free passage for the heads of the tacks. To hold the tacks in the raceway the head of the lowermost tack is engaged by a gate 118 (Figs. 12, 13 and 17) which is pivoted on the head 76 and normally held in tack-engaging position by a pin 119 (Fig. 17) engaged with a fin 120 formed on the back of the gate. The tacks 110 are withdrawn one at a time from the raceway 116 and passed through an opening 121 (Fig. 17) in the throat 74 down which they fall until stopped by a pair of leaf springs 122 (Fig. 19), carried by the nozzle 75, 120 which straighten the tacks to insure their proper engagement by the end of the driver. 115

In order to properly handle a tack from the time it leaves the raceway until it is delivered to the throat 74 the nozzle 75 is extended rearwardly to form a vertical ledge 123 (Figs. 12 and 13) arranged beneath the end of the raceway 116 and in the vertical plane thereof. The space between the bottom of the raceway and the upper surface of 130

the ledge 123 is so small that but one tack at a time can fall from the raceway upon the ledge when the gate is periodically lifted during the operation of the machine.

5 Mounted to straddle the stationary ledge 123 is a picker 124 (Figs. 12, 13 and 14) which reciprocates on the top edge 125 of the nozzle 75 between the plates 117. The picker 124 is provided with a slot 127 (Fig. 15) which extends from the front end of the picker to a point near its rear end. Centrally located on the picker 124 is a shoulder 128 (Figs. 12, 13 and 14) shaped to engage beneath the head of a tack. When the gate 118 is elevated the lowermost tack in the raceway falls upon the picker 124 at the rear of the shoulder 128. The head of the tack rests upon the top of the picker and the shank of the tack passes through the slot 127 and rests upon the top of the ledge 123. Then the picker is moved rearwardly. The tack on the top of the picker is prevented from moving rearwardly with the picker owing to the limited space between the top of the picker and the end of the raceway. Continued rearward movement of the picker positions the head of the tack in the shoulder 128 whereupon the picker is moved forwardly. During the forward movement of the picker the shank of the tack drags over the ledge until it is withdrawn therefrom and then the tack swings downwardly under the influence of gravity until the tack rests upon the top of the picker in front of the shoulder 128. At this time a transferring device 129 (Figs. 12, 13 and 14) sweeps through the slot 127 and pushes the head of the tack through a guideway 130 (Fig. 15) formed between two plates 131 carried by the picker 124 and into the throat 74. As shown in Fig. 12 the transferring device 129 closes the opening 121 in the throat 74 at the end of the transferring movement in order to obviate all danger of the point of the tack striking the floor of the opening 121 and thus become tipped across the throat and jammed therein upon the descent of the driver.

In order to elevate the gate 118 to release the end tack the gate carries a pin 132 (Figs. 12, 13 and 14) which is embraced by a slot 133 formed in one end of a link 134 pivoted to a post 135 projecting laterally from a lever 136 pivoted at 137 to the head 76. The upper end of the lever 136 is connected to one end of a link 138 the other end of which is provided with a roll (not shown) engaged with a cam groove 139 (Fig. 18) formed in the inside face of the disk 98.

60 The picker 124 is reciprocated, in the manner described to pick the tack from the ledge 123 and position the tack for the operation of the transferring device 129, by the same lever 136 that operates the gate 118. To this end the lower end of the lever

136 is provided with a laterally extending post 140 which is connected to the side of the picker. The times of operation of the gate 118 and picker 124 are such that the gate is elevated to permit a tack to drop off the end of the raceway 116 at about the end of the forward stroke of the picker, the difference in timing being permitted by the slot 133.

The transferring device 129 depends from a lateral extension 141 (Fig. 15) of an arm 142 (Figs. 12, 13 and 14) which depends from a sleeve 143 pivoted on a horizontal stud 144 on the head 76. A second arm 145 on the sleeve 143 carries a block 146 (Fig. 11) which is connected to a link 147 by a yielding connection to permit the transferring device to yield, if a tack becomes jammed in the slot 121, and thus prevent breakage. To this end a rod 148 (Fig. 11) connected to the block 146 passes loosely through an extension 149 on the link 147. Coiled around the rod 148 is a spring 150 interposed between the extension 149 and suitable adjusting and locking nuts 151 on the rod. The other end of the link 147 is slotted (Fig. 14) to embrace the shaft 94 and is provided with a roll 152 engaged with a cam groove 153 in the outside face of the disk 98.

95 The tacker is arranged to operate in the position shown in Fig. 1, hereinafter called "the fastening-inserting station," to drive tacks in the strip of overdrawn upper exposed on the shoe bottom between the back edges of the wipers and the edge of the shoe bottom. While the tacker is driving tacks it is continuously moved around the heel seat of the shoe from one breast corner to the other. During this movement of the tacker the nozzle 75 is pressed laterally against the back edges of the wipers so that during the traveling movement of the tacker the wipers act as a guide and the nozzle as a gage co-operating with the guide to direct the traveling movement of the tacker.

To press the nozzle 75 laterally against the back edges of the wipers the head 76 is carried upon a flat plate 154 (Fig. 26) which is pivoted at its rear end upon a pin 155 carried by a second flat plate 156. The plate 156 is pivoted near its front end upon a pin 157 carried by a slide 158 mounted to embrace and slide upon ways 159 (Fig. 24) formed in a horizontal extension 160 of the vertical slide 107. The plate 156 carries a spring chamber 161 (Fig. 20) in which is mounted a rod 162 which passes through the chamber 161 below the tacker head 76 (Fig. 26). Mounted on the rod 162 is a pair of sleeves 163 (Fig. 20) having heads 164 (Fig. 26) arranged to engage the tacker head 76. Coiled around each of the sleeves 163 is a spring 165 (Fig. 20) which is interposed between the head 164 and a washer 166, on 130

the rod 162, which is held against the exterior of the spring chamber 161 by a nut 167.

In order to move the nozzle 75 through a predetermined path which is the same for all sizes and styles of shoes operated upon the lower end of the pin 155 passes loosely into a guideway 168 (Fig. 21) having substantially a horse-shoe formation. The guideway 168 is formed in a plate 169 secured to the slide 107. The pin 155 when positioned in one end of the guideway 168 fits into a semi-cylindrical notch 170 (Fig. 23) formed in a rack 171 (Fig. 21) mounted 10 to slide in a way 172 formed in the extension 160. The rack 171 carries the pin 155 along the guideway to the juncture of the straight and curved portions thereof at which time a semi-cylindrical notch 173 15 formed in the peripheral edge of a rotary disk 174 (Figs. 21, 23 and 26) engages the pin 155 and removes it from the rack 171 and transfers the pin along the curved portion 20 of the guideway 168. At the other juncture of the curved and straight portions 25 of the guideway 168 the pin 155 leaves the notch 173 and enters a semi-cylindrical notch 175 (Fig. 23) formed in a rack 176 mounted to slide in a way 177 formed in 30 the extension 160.

The nozzle 75 is thus transferred around the heel seat from one breast corner to the other breast corner. The guideway 168 is smaller than the tacking line on the smallest 35 shoe operated on by the machine. The springs 163 by pressing the nozzle 75 laterally against the wipers permit the nozzle to traverse a path determined by the wipers for each shoe operated upon which will be 40 different from the path determined by the guideway 168.

The disk 174 is mounted near the upper end of a vertical shaft 178 (Fig. 26) journaled in the extension 160. The lower 45 end of the shaft 178 is provided with a worm wheel 179 which is driven by a worm 180 (Fig. 25) formed on a shaft 181. The shaft 181 is provided at its rear end with a bevel gear 182 (Fig. 22) which meshes 50 with a pair of bevel gears 183 loosely journaled on the shaft 110 and bearing 111. Interposed between the bevel gears 183 is a clutch sleeve 184, splined on the shaft 110, having clutch teeth arranged to alternately 55 engage similar teeth formed on the bevel gears 183. The shaft 178 also drives the racks 171 and 176 in opposite directions through a gear 185 on the shaft.

The nozzle 75 is transferred first from 60 the breast corner A to the breast corner B (Figs. 20 and 21) in operating upon one shoe and then from the breast corner B to the breast corner A in operating upon the succeeding shoe. In order to shift the 65 clutch sleeve 184 to drive the shaft 178 first

in one direction to transfer the nozzle from A to B when operating upon one shoe and then in the other direction when operating upon the succeeding shoe the clutch sleeve 184 (Fig. 22) is embraced by a yoke 186 70 projecting from a rock shaft 187 journaled in the bearing 111. The rock shaft 187 is provided with a depending arm 188 which is connected to a sliding link 189 (Figs. 1 and 21) mounted to slide in an arm 190 secured to the extension 160. The link 189 is shifted in the arm 190 by a handle 191 which is secured to a plate 192 pivoted at 75 193 on the extension 160 and having a limited amount of play between lugs 194 and 195 (Fig. 21) in the link 189. The link 189 is normally held in neutral position with the clutch sleeve 184 disengaged from both of the bevel gears 183 by a spring latch 196, on the arm 190, which is arranged to engage 80 the center one of the three notches 197 formed near the free end of the link 189. When the nozzle 75 is at the breast corner A and it is desired to start the machine to cause the nozzle to travel around the heel 85 seat to a corner B the handle 191 is pulled toward the operative thus causing the link 189 to slide forwardly to clutch the upper bevel gear 183 to the shaft 110. The clutch is held in by the latch 196 which rides out of 90 the central notch 197 during the forward movement of the link and into the rear notch 197. When the nozzle 75 is to be moved from the breast corner B to the breast corner A the handle 191 is pushed away from 95 the operative thus clutching the lower bevel gear 183 to the shaft 110 and causing the latch to ride into the front notch 197.

In order to simultaneously throw in the drive for the tack inserting mechanism when 100 the clutch sleeve 186 is moved in either direction the clutch sleeve 113 is engaged by a yoke 198 (Fig. 21) projecting from a rock shaft 199 (Fig. 22) by a toggle 201 one arm of which is linked to the arm 200 105 and the other arm of which is secured to the rock shaft 187. When the clutch sleeve 186 is in neutral position the toggle 201 is straightened as shown in Fig. 22. When the clutch sleeve 186 is shifted in either direction to start the mechanism for feeding the tacker the toggle is broken thus sliding the clutch sleeve 113 into engagement with the bevel gear 109 and thereby starting the driving 110 for the tack inserting mechanism.

In order to automatically stop the tacker when it reaches the breast corner B the plate 192 is provided with an incline 202 arranged in the path of movement of a stop pin 203. When the pin 203 engages the incline 202 115 the plate 192 is shifted on its pivot to move the link 189 rearwardly thus returning the clutch sleeve 184 to its neutral position and the latch 196 to the central notch 197. The tacker is automatically stopped when it 120 125 130

reaches the breast corner A by a second incline 205 on the plate 192 which is engaged by the stop 203 to tip the plate 192 on its pivot and thus slide the link forwardly to bring the clutch sleeve 184 into neutral position. As the lengths of the heel seats vary in different sizes of shoes it is desirable to vary the stopping position of the tack in accordance with the variations in the length 5 of heel seat operated upon. To this end the pin 203 is carried by a block 206 which is mounted for adjustment along a slot 207 formed in the plate 204. The block 206 is adjusted in the slot 207 to vary the stopping point on shoes of different sizes by a screw 208, threaded into the block 206, mounted on the plate 204.

When the nozzle 75 is located at the breast corner A the head 76 may be moved from 20 the fastening-inserting station to a fastening-storage station in which station the raceway 116 is alined with a raceway 209 in order that the supply of tacks in the raceway 116 may be replenished. To this end 25 the slide 107 (Fig. 25) is mounted to slide in ways 210 formed in the column 108. The weight of the slide and its associated parts is counterbalanced by a weight 211 (Figs. 1 and 2) which is connected to the slide 107 30 by ropes 212 (Fig. 25) passing over pulleys 113 (Fig. 28) on the column 108. To move the slide 107 to position the tacker at the fastening-inserting station or at the fastening-storage station the slide 107 is connected 35 to a link 214 (Fig. 1) the lower end of which is connected to an arm 215 projecting from a rock shaft 216 journaled in the base 9. A second arm 217 projecting from the rock shaft 216 is provided with a handle 218 in 40 convenient position for manipulation by the operative.

The raceway 209 is loosely received between a pair of vertical plates 219 rising from an extension 220 of the column 108. 45 The raceway 209 is yieldingly held between the plates 219 by a leaf spring 221 one end of which is secured to the raceway 209 and the side of which is pressed upon by the ends of a pair of screws 222 secured to one of 50 the plates 219. The raceway 209 supports the heads of the tacks which are covered by a cover 223 spaced from the raceway. The tacks in the storage raceway 209 are held therein by a gate 224 which is pivoted at 225 55 on one of the plates 219. The gate 224 is normally held in tack-engaging position by a leaf spring 226, on the back of the gate, which is engaged by a pin 227 on one of the plates 219. The shanks of the tacks de- 60 pending through the roadway near the end of the raceway 209 are alined with the roadway by a pair of wedge-shaped blocks 228 (Fig. 32) which are supported at the lower ends of leaf springs 229 supported at their 65 upper ends by a bridge 230 secured to the

raceway 209. When the raceway 116 is elevated into the fastening-storage station a fin 231 on the raceway 116 engages a pin 232 on the gate 224 and elevates the gate against the tension of the spring 226. At 70 the same time the plates 117 at the upper end of the raceway 116 engage the wedge blocks 228 and spread them apart thus permitting the alined tacks to slide from the raceway 209 into the raceway 116. When 75 the raceway 116 is withdrawn from the raceway 209 the gate 224 and blocks 228 return to their initial positions under the influence of the springs 226 and 229, respectively, in readiness to act upon a new lot of 80 tacks presented for storage to the raceway 209.

The raceway 116 is in line with the storage raceway 209 only when the nozzle 75 at the fastening-inserting station is located 85 at the breast corner A (Figs. 20 and 21). As the breast corner A will vary with different shoes it is desirable to provide some means for positively limiting the elevated position of the raceway 116 so that it will 90 always be in line with the raceway 209 whether the shoe last operated upon is large or small. To this end the slide 158 carries an arm 233 (Fig. 20) which is provided at its free end with a block 234 (Fig. 22) 95 having an inclined face 235 arranged to co-operate with an inclined face 236 on a block 237 carried by the column 108. The inclines of the faces 235 and 236 are parallel to the incline of the raceways 116 and 209 so that 100 the raceways 116 and 209 will always aline when the raceway 116 is moved into the fastening-storage station notwithstanding variations in the stopping position of the nozzle 75 at the breast corner A for different sizes of shoes. 105

In order to provide means for automatically bringing the starting and stopping link 189 into neutral position when the tacker head is elevated, during its operation, to withdraw it from the fastening-inserting station the column 108 carries a rib 238 having a V-shaped end which enters between a pair of blocks 239 on the link 189. If the driving mechanism for the tacker is 110 stopped when the tacker head is elevated the rib 238 enters between the two blocks 239 and prevents the starting of the driving mechanism for the tacker while it is moving toward or from the storage station. If the 115 driving mechanism for the tacker are in operation when the tacker head is elevated the lower end of the rib 238 wedges itself between the blocks 239 and shifts the link 189 into neutral position from either its 120 advanced or its retracted position.

In order to provide the storage raceway 209 with tacks the column 108 supports a hopper 240 which is loosely mounted on one end of a stationary rod 241 secured to the 130

column 108. A gear 242, secured to the hopper 240 and loosely mounted on the rod 241, meshes with a pinion 243, on a shaft 244, journaled in the column 108 and driven 5 from the vertical shaft 110 by bevel gears 245 and 246 on the shafts 110 and 244, respectively. The hopper 240 is thus continuously rotated during the operation of the machine to tumble a mass of tacks in the 10 bottom thereof. The mass of tacks is inserted into the hopper 240 through a filling funnel 247 which is pivoted on one of the plates 219 so that it may be tipped back to expose an opening 248 in the front face of 15 the hopper for the purpose of inspection or repair. The interior of the hopper 240 is provided with a pair of buckets 249 each of which carries a pair of rails 250 spaced to provide a tack slot 251 theretwixen. 20 The buckets 249 are provided with sloping walls 252 in order to direct the points of the tacks caught by the buckets into the slot 251. With this construction the buckets 249 are alternately passed through the mass of 25 tumbled tacks in the hopper. Some of the shanks of the tacks will be deflected by the sloping walls 252 into the slot 251. Thereafter the heads of the tacks will assemble on the rails 250 until during the rotation of 30 the hopper the ends of the rails register with a curved stationary raceway 253 carried by the rod 241. Then the tacks assembled on the rails 250 slide therefrom and into the raceway 253. The lower end of 35 the raceway 253 and the upper end of the raceway 209 are separated by a gap 254 (Fig. 28). The inclines of the raceways are such that the tacks delivered to the raceway 253 jump the gap and pass into 40 the raceway 209 under the force of gravity. When the storage raceway 209 is full of tacks the tacks from the raceway 253 spill into the hopper 240.

In order to insure that no tacks will remain on the rails 250 after they pass the 45 point of registration with the raceway 253 the lower ends of the rails 250 are permitted to spring apart as shown in Fig. 33, after the point of registration with the raceway 50 253 has been passed, to dump all the tacks remaining on the rails into the hopper. To wedge them back into a position in which they will properly support the heads of the tacks the support for the raceway 253 is 55 provided with a curved way 255 (Fig. 29) having sloping walls at its entrance. The distended rails 250 engage the sloping walls and are wedged thereby back into the dotted line position (Fig. 33). The way 255 then 60 holds the rails 250 with the proper space between them until the point of registration with the raceway 253 is passed when the rails 250 pass out of the way 255 and spread apart to dump any tack still held on the

rails. The entrance to the way 255 is 65 guarded by a pair of spring metal flaring wings 257 which prevent a tack from jamming between the entrance to the way 255 and the rails 250.

In order to provide a friction drive for the 70 hopper 240 and thus prevent breakage in case a tack becomes jammed therein the shaft 244 is made in two parts (Fig. 28) each part having a collar 258 thereon. Between the collars 258 a leather disk 259 is pinched the 75 construction being such that the disk 259 permits the left hand collar 258 (Fig. 28) to slip thereover when a jammed tack stops the rotation of the hopper.

It is found that the heel seats of some 80 shoes slope upwardly from the breast line toward the back of the shoe while in others the heel seats slope upwardly from the back of the shoe toward the breast line. In order to maintain the nozzle 75 at a uniform distance above the work notwithstanding these variations in the slope of the heel seats the machine of the drawings is provided with a cam 260 (Fig. 1) comprising a flat plate, 85 loosely mounted on the top of the bridge 90 48. The cam 260 is pivoted on a pair of vertical rods 261 mounted to slide through the bridge 48. The lower ends of the rods 261 carry a horizontal bar 262 extending transversely of the shoe. The cam 260 is engaged by a horizontal gage rod 263 which is supported between a pair of arms 264 secured to the slide 158. In its normal position upon the top of the bridge 48 the cam 260 is inclined to maintain the nozzle 75 95 through the height gage 263, at a uniform height above the heel seat of a shoe which slopes upwardly from the breast line to the back of the shoe. When the heel seat of a shoe operated upon is in a horizontal plane 100 or slopes upwardly from the back of the shoe to the heel seat the handles 72, of the wipers, as they move over the shoe bottom during the wiping movement of the wipers 110 engage beneath the bar 262 and elevate the pivoted end of the cam 260 and thereby incline the cam 260 on the top of the bridge 48 to position the surface engaged by the gage 263 parallel to the heel seat engaged by the wipers. 115

In its normal idle position the tacker head 76 is at the fastening-storage station with the raceways 116 and 209 engaged to permit tacks to flow from the raceway 209 into the raceway 116. The electric motor is now 120 thrown in to rotate the hopper 240 to supply the raceway 209 with tacks. When a partially lasted shoe is jacked on a leader and positioned upon the table 7 between the gage plates 12 and 19 the treadle 27 is depressed to lock the leader upon the table, to engage the gage 55 with the heel seat of the sole, and to apply the pressure mechanism 125

to the gage 55. The treadle 27 is then moved laterally beneath the locking lug 30 to lock the parts controlled therefrom in their operative positions. The handles 72 are then 5 grasped by the operative and manipulated to cause the wipers to initially engage the shoe. As shown in Fig. 5 in this initial position the wipers engage the upper just below the exposed face of the sole on the bottom 10 of the last. Further closing movement of the handles 72 causes the wipers to slide upwardly over the face of the heel thus stretching the upper thereon or, stated in another way, imparting an updraw movement 15 to the upper. During the upward movement of the wipers the gage 55 is raised from the sole thus causing the entire pressure of the pressure mechanism to be transmitted to the work through the wipers 20 (Fig. 6). Continued closing movement of the handles 72 causes the wipers to wipe the updrawn upper over the bottom of the heel seat (Fig. 7). During the closing movement 25 of the handles 72 the cam 260 is adjusted to conform to the longitudinal slope on the heel seat.

The handle 218 (Fig. 1) is now elevated to withdraw the tacker head 76 from the fastening-storage station and to position the 30 nozzle 75 at the breast corner A on the heel seat. The handle 191 (Fig. 21) is then pulled toward the operative to throw in the driving mechanisms for driving the tacks and for feeding the tacker. The nozzle 75 35 is now driven around the wipers. During this traveling movement of the nozzle 75 the tacks are inserted in the heel seat to secure the overdrawn upper held clamped by the wipers. When the nozzle 75 approaches the 40 breast corner B the pin 203 (Fig. 22) engages the incline 202 and throws out the driving mechanisms for driving tacks and for feeding the tacker.

The handle 218 is now depressed to elevate 45 the tacker head 76 a short distance to bring the nozzle 75 above the wipers. The treadle 27 is then released to free the work from the arms 18 and to return the wipers to their original inoperative position. Another 50 shoe is then positioned on the table 7 and heel lasted. When the nozzle 75 is engaged with the work and the driving mechanisms therefor thrown into operation the traveling tacker will insert tacks from the breast corner B to the breast corner A at 55 which point the driving mechanisms will be automatically thrown out through the engagement of the pin 203 with the incline 205. When the nozzle 75 is again elevated to 60 clear the wipers advantage may be taken of its alinement with the raceway 209 to return the raceway 116 to the fastening-storage station and thus replenish the raceway 116 with tacks.

The nozzle 75 may be fed by hand, when 65 the driving mechanism therefor is thrown out of operation, through a handle 265 (Fig. 1) on the end of the shaft 181.

It will be apparent to those skilled in this 70 class of machines that changes may be made in the details of structure, the described and illustrated embodiment thereof, being intended as an exploitation of its underlying essentials, the features whereof will be definitely stated in their true scope in the claims 75 hereto appended.

What is claimed as new, is:—

1. A lasting machine, having, in combination, end lasting mechanism and a carrier therefor connected thereto, the projection of 80 any part of the connection between the end lasting mechanism and its carrier upon the plane of the shoe bottom lying upon the shoe bottom entirely within the edge thereof throughout the operating stroke of the end 85 lasting mechanism, substantially as described.

2. A lasting machine, having, in combination, a carrier, and an end lasting mechanism having a plural point suspension on the 90 carrier, the projections of said points upon the plane of the shoe bottom lying upon the shoe bottom throughout the operating stroke of the end lasting mechanism, substantially 95 as described.

3. A lasting machine, having, in combination, a shoe support, and an end lasting mechanism constructed and arranged for lateral movement about a center located above the shoe bottom between the ends thereof, 100 substantially as described.

4. A lasting machine, having, in combination, a shoe support, and an end lasting mechanism constructed and arranged for movement longitudinally of the shoe about 105 centers located above the shoe bottom between the ends thereof, substantially as described.

5. A lasting machine, having, in combination, a shoe support, and a hinged wiper 110 mechanism constructed and arranged for vertical movement about an axis located above the plane of the shoe bottom, substantially as described.

6. A lasting machine, having, in combination, a shoe support, and a hinged wiper 115 mechanism constructed and arranged for vertical movement about a horizontal axis located above the plane of the shoe bottom, substantially as described.

7. A lasting machine, having, in combination, a shoe support, and an end lasting mechanism constructed and arranged for vertical movement about an axis located above the plane of the shoe bottom and for 125 longitudinal rocking movement about an axis located substantially in the plane of the shoe bottom, substantially as described.

8. In a lasting machine, wipers for wiping the upper over the shoe bottom, said wipers being located entirely within the edge of the shoe bottom at the completion of the wiping stroke, substantially as described. 5
9. In a lasting machine, a wiper comprising a pair of pivoted fingers, the pivot therefore being located entirely within the edge of the shoe bottom both at the beginning and 10 at the completion of the wiping stroke, substantially as described.
10. A lasting machine, having, in combination, a carrier, a pair of struts depending therefrom, and a wiper carried by the lower 15 ends of the struts, substantially as described.
11. A lasting machine, having, in combination, a carrier, a pair of struts universally connected at their upper ends to the carrier, and a wiper universally connected to the 20 lower ends of the struts, substantially as described.
12. A lasting machine, having, in combination, a carrier, a pair of struts universally connected at their upper ends to the carrier, 25 a wiper universally connected to the lower ends of the struts, and a third strut universally connected at one end to the wiper and mounted at its other end to slide in the carrier, substantially as described.
13. In a lasting machine, an end lasting 30 wiper comprising a pair of narrow spring fingers pivoted together and having a flat operating surface, substantially as described.
14. In a lasting machine, wipers for wiping the upper over the shoe bottom, the entire rear faces of said wipers being separated from the edge of the shoe bottom by a strip of overdrawn upper at the completion 35 of the wiping stroke, substantially as described.
15. A lasting machine, having, in combination, an end lasting mechanism, and a gage engaged with the shoe bottom for controlling the initial operative position of the 40 end lasting mechanism with relation to the shoe bottom and removed from the shoe during the operating stroke of the end lasting mechanism, substantially as described.
16. A lasting machine, having, in combination, a shoe support, wipers for wiping the upper over the shoe bottom, and a gage engaged with the shoe bottom for controlling the initial operative position of the 45 wipers with relation to the shoe bottom and removed from the shoe during the operating stroke of the end lasting mechanism, substantially as described.
17. A lasting machine, having, in combination, a shoe support, a pivoted lever, a gage carried by the lever and having a rigid connection therewith, and pressure mechanism acting upon the lever for pressing the gage upon the shoe bottom, sub- 50 stantially as described.
18. A lasting machine, having, in combination, a shoe support, a lever of the first order, a gage carried near one end of the lever and having a rigid connection therewith, and pressure mechanism acting near 55 the other end of the lever for pressing the gage yieldingly on the shoe bottom, substantially as described.
19. A lasting machine, having, in combination, a shoe support, a gage, and pressure mechanism for pressing the gage upon the shoe bottom including a toggle having a yielding arm, substantially as described. 75
20. A lasting machine, having, in combination, a shoe support, a gage, pressure mechanism for pressing the gage on the shoe bottom, and means under the control of the operator for elevating the gage from the shoe bottom against the pressure of the pressure mechanism, substantially as de- 80 scribed.
21. A lasting machine, having, in combination, a shoe support, a gage, a pressure mechanism including a toggle having a yielding arm for pressing the gage upon the 85 shoe bottom, and means for operating the toggle to apply the gage to the shoe bottom and the pressure mechanism to the gage, substantially as described.
22. A lasting machine, having, in combination, a shoe support, a gage, a pressure mechanism including a toggle having a yielding arm for pressing the gage upon the shoe bottom, means for operating the toggle to apply the gage to the shoe bottom and the pressure mechanism to the gage, and a stop for limiting the extent of movement of 90 said means, substantially as described. 95
23. A lasting machine, having, in combination, a shoe support, a gage, a pressure mechanism including a toggle having a yielding arm for pressing the gage upon the shoe bottom, means for straightening the toggle to apply the gage to the shoe bottom and the pressure mechanism to the gage, and a stop for preventing the complete making 100 of the toggle, substantially as described. 105
24. A lasting machine, having, in combination, a shoe support, a gage, a pressure mechanism including a toggle having a yielding arm for pressing the gage upon the shoe bottom, means for straightening the toggle to apply the gage to the shoe bottom and the pressure mechanism to the gage, and a stop for preventing the complete making 110 of the toggle, and a lock for holding the arms of the toggle in the position determined by the stop, substantially as described.
25. A lasting machine, having, in combination, a shoe support, a wiper carrier, a gage mounted on the carrier, pressure mechanism for holding the gage upon the shoe bottom, and wipers mounted on the carrier and arranged to be initially engaged 115
- 120
- 125
- 130

with the work substantially below the plane of the shoe bottom and then closed on the shoe, the wipers during their closing movement updrawing and overdrawing the upper and elevating the gage against the pressure of the pressure mechanism, substantially as described.

26. A lasting machine, having, in combination, a wiper carrier, a bearing foot or gage thereon, pressure mechanism for forcibly pressing the foot against the shoe bottom, and wipers on the carrier constructed and arranged to transmit the pressure of the pressure mechanism to the work in the place of the bearing foot during the wiping operation, substantially as described.

27. A lasting machine, having, in combination, pressure mechanism, a wiper carrier having wipers and a bearing foot or gage supported thereby, and means for transmitting the pressure mechanism to the shoe first through the bearing foot and then through the wipers, substantially as described.

28. A lasting machine, having, in combination, a centrally pivoted wiper carrier, pressure mechanism arranged to act upon one end of the carrier, wipers and a bearing foot or gage supported by the other end of the carrier, and means for transmitting the pressure of the pressure mechanism to the shoe first through the bearing foot and then through the wipers, substantially as described.

29. A lasting machine, having, in combination, a wiper carrier, pressure mechanism for forcibly pressing the wiper carrier toward the shoe bottom, and normally floating wipers arranged to be wedged up the back of the shoe and over the shoe bottom against the pressure of the pressure mechanism, substantially as described.

30. In a lasting machine, a gage movable laterally about a single axis the projection of which upon the plane of the shoe bottom and upon the line of the produced axis lies entirely within the edge of the shoe bottom, substantially as described.

31. In a lasting machine, a laterally movable gage, and a spring for normally holding the gage substantially in the median line of the shoe bottom, substantially as described.

32. A lasting machine, having, in combination, a lasting head, uprights rising therefrom, a wiper carrier having a pivotal connection with said uprights, and pressure mechanism acting upon one end of the wiper carrier for pressing it toward the shoe bottom, substantially as described.

33. A lasting machine, having, in combination, a lasting head, uprights rising therefrom, a wiper carrier having a pivotal connection with said uprights, and pressure mechanism including a toggle having a

yielding arm acting upon one end of the wiper carrier for pressing it toward the shoe bottom, substantially as described.

34. A lasting machine, having, in combination, a lasting head, uprights rising therefrom, a wiper carrier having a pivotal connection with said uprights, and pressure mechanism acting upon one end of the wiper carrier for pressing it toward the shoe bottom, said mechanism including a toggle having its opposite ends pivoted to the lasting head and wiper carrier, respectively, substantially as described.

35. A lasting machine, having, in combination, a lasting head, uprights rising therefrom, a wiper carrier having a pivotal connection with said uprights, and pressure mechanism, including a toggle, acting upon one end of the wiper carrier for pressing it toward the shoe bottom, and a treadle for partially making the toggle, substantially as described.

36. A lasting machine, having, in combination, a lasting head, uprights rising therefrom, a wiper carrier having a pivotal connection with said uprights, pressure mechanism including a toggle acting upon one end of the wiper carrier for pressing it toward the shoe bottom, and a treadle movable vertically for partially making the toggle and movable laterally for locking the toggle in its partially made position, substantially as described.

37. A lasting machine, having, in combination, a lasting head, uprights rising therefrom, a wiper carrier having a pivotal connection with said uprights, pressure mechanism including a toggle having a yielding arm acting upon one end of the wiper carrier for pressing it toward the shoe bottom, and a treadle movable vertically for partially making the toggle and movable laterally for locking the toggle in its partially made position, substantially as described.

38. A lasting machine, having, in combination, a lasting head, upright rising therefrom, a yoke carried by the uprights, said yoke having its arms extending substantially longitudinally of the shoe, said arms being joined by an arch bridge extending transversely of the shoe, and a wiper carrier on the bridge, substantially as described.

39. A lasting machine, having, in combination, a lasting head, uprights rising therefrom, a yoke carried by the uprights, said yoke having its arms extending substantially longitudinally of the shoe, said arms being joined by an arch bridge extending transversely of the shoe, a wiper carrier on the bridge, and a gage at the middle of the bridge, substantially as described.

40. A lasting machine, having, in combination, a lasting head, uprights rising therefrom, a yoke carried by the uprights, said yoke having its arms extending substantially

longitudinally of the shoe, said arms being joined by an arch bridge extending transversely of the shoe, and a wiper carrier on the back end of the bridge suspended over the space between the arms, substantially as described.

41. A lasting machine, having, in combination, a lasting head, uprights rising therefrom, a yoke carried by the uprights, 10 said yoke having its arms extending substantially longitudinally of the shoe, said arms being joined by an arch bridge extending transversely of the shoe, a wiper carrier on the bridge, and wipers on the carrier 15 movable in the space between the arms, substantially as described.

42. A lasting machine, having, in combination, a stationary work support, pressure mechanism, and wipers movable vertically on the back of the shoe on the support 20 against the pressure of the pressure mechanism for updrawing the upper, substantially as described.

43. A lasting machine, having, in combination, wipers movable over the shoe bottom to overdraw the upper engaged by the 25 bottom faces of the wipers, and pressure mechanism thrown into operation by the act of closing the wipers on the shoe acting upon 30 the upper faces of the wipers, substantially as described.

44. A lasting machine, having, in combination, wipers movable over the shoe bottom to overdraw the upper engaged by the 35 bottom faces of the wipers, and pressure mechanism thrown into operation by the act of closing the wipers on the shoe acting vertically 40 on the wipers to compress the upper engaged by the bottom faces of the wipers, substantially as described.

45. A lasting machine, having, in combination, a carrier, a pair of struts universally connected at the upper ends to the carrier, and a wiper comprising a pair of 45 jointed sections, each section being universally connected to the lower end of one of the struts, substantially as described.

46. A lasting machine, having, in combination, end lasting wipers movable from 50 one end of the shoe toward the other, and devices for moving the wipers, said devices being mounted in advance of the active edges of the wipers, substantially as described.

55. 47. A lasting machine, having, in combination, wipers comprising a pair of jointed sections movable bodily from one end of a shoe toward the other to wipe the upper over 60 the shoe bottom, and a pair of handles, connected to the sections, in advance of the active edges of the wipers for closing and moving the wipers, substantially as described.

48. A lasting machine, having, in com-

bination, wipers for wiping the upper over 65 the shoe bottom, the back or inactive edges of said wipers being separated from the edge of the shoe bottom by a strip of overdrawn upper at the completion of the wiping stroke, and means for inserting fastenings through the strip of overdrawn upper, 70 substantially as described.

49. A lasting machine, having, in combination, wipers for wiping the upper over 75 the shoe bottom, means for inserting fastenings in the overdrawn upper, and means for relatively actuating the wipers and inserting means to transfer the point of operation of the inserting means around the wipers, 80 substantially as described.

50. A lasting machine, having, in combination, wipers for wiping the upper over the shoe bottom, means for inserting fastenings in the overdrawn upper, and means for moving the inserting means around the 85 wipers, substantially as described.

51. A lasting machine, having, in combination, automatic upper fastening-inserting means including a gage, and a guide for the gage comprising a clamp for holding the 90 upper in overdrawn position, substantially as described.

52. A lasting machine, having, in combination, wipers for wiping the upper over 95 the last bottom, and automatic upper fastening-inserting means including a gage, said gage coöperating with the back faces of the wipers for controlling the relative position of the shoe and inserting means, substantially as described.

53. A lasting machine, having, in combination, a shoe support, wipers for wiping the upper over the last bottom, means for inserting fastenings, a gage carried by the inserting means, and means for relatively 105 actuating the shoe and inserting means to transfer the point of engagement of the gage along the back edges of the wipers, substantially as described.

54. A lasting machine, having, in combination, a shoe support, wipers for wiping the upper over the last bottom, and means for inserting fastenings along a line between the edge of the shoe bottom and the wipers while the upper is held clamped by the 115 wipers, substantially as described.

55. A lasting machine, having, in combination, an end lasting mechanism for lasting the upper over the shoe bottom, and means for securing the lasted upper along a 120 line between the end lasting mechanism and the edge of the shoe bottom, substantially as described.

56. A lasting machine, having, in combination, wipers for wiping the upper over 125 the last bottom, a tack nozzle arranged to engage the back edges of the wipers, and means for relatively actuating the wipers

and nozzle to transfer the point of operation of the nozzle around the wipers, substantially as described.

57. A lasting machine, having, in combination, a clamp for holding the upper in lasted position arranged to engage the upper along a line separated from the edge of the shoe bottom, and means for inserting fastenings in the space between the clamp and the edge of the shoe bottom, substantially as described.

58. A lasting machine, having, in combination, a guide constructed to engage the overlaid uppers along a line spaced from the edge of the shoe, and means for inserting fastenings in the upper between the guide and the edge of the shoe, substantially as described.

59. An end lasting machine, having, in combination, a shoe support, wipers for wiping the upper at an end of the shoe, a tacker, and means for feeding the tacker to transfer its point of operation around the end of the shoe to secure the upper in lasted position, substantially as described.

60. A shoe machine, having, in combination, a shoe support, a guide engaged with the shoe, operating means including a gage, and mechanism for transferring the gage along the guide comprising a pair of racks movable in opposite directions, substantially as described.

61. A shoe machine, having, in combination, a shoe support; a guide engaged with the shoe; operating means including a gage; and mechanism for transferring the gage along the guide comprising a pair of racks movable in opposite directions, a slideway adjacent the racks, a pin mounted to slide in the slideway, and a transerrer for transferring the pin in the slideway from one rack to the other rack, substantially as described.

62. A shoe machine, having, in combination, a shoe support; a guide engaged with the shoe; operating means including a gage; and mechanism for transferring the gage along the guide comprising a pair of racks movable in opposite directions, each rack having a notch in one face, a slideway adjacent the racks, a pin mounted to slide in the slideway arranged to engage a notch in one of the racks, and a transerrer for removing the pin from the notch in one of the racks and positioning it in the notch in the other rack, substantially as described.

63. A shoe machine, having, in combination, a shoe support; a guide engaged with the shoe; operating means including a gage; and mechanism for transferring the gage along the guide comprising a pair of racks movable in opposite directions, each rack having a notch in one face, a guideway adjacent the racks, a pin mounted to slide in

the guideway arranged to engage a notch in one of the racks, and a rotary disk for removing the pin from the notch in one of the racks and positioning it in the notch in the other rack, substantially as described.

64. A shoe machine, having, in combination, a shoe support; a guide engaged with the shoe; operating means including a gage; and mechanism for transferring the gage along the guide comprising a pair of racks movable in opposite directions, each rack having a semi-circular notch in one face, and a rotary disk having a semi-circular notch in its edge arranged to register at different times with the notches in the racks, substantially as described.

65. A shoe machine, having, in combination, operating means including a gage; a guide; mechanism tending to move the gage through a predetermined path; and connections between the gage and said mechanism permitting the gage to move through a path determined by the guide, substantially as described.

66. A shoe machine, having, in combination, a shoe support; a guide engaged with the shoe; operating means including a gage; means for pressing the gage yieldingly against the guide; and means for moving the gage through a predetermined path, substantially as described.

67. A shoe machine, having, in combination, a shoe support; a guide engaged with the shoe; operating means including a gage; a slide for the operating means; means engaging the slide for pressing the gage yieldingly against the guide; and mechanism tending to move the gage through a predetermined path, substantially as described.

68. A lasting machine, having, in combination, wipers for wiping the upper over the shoe bottom, means for inserting fastenings in the overdrawn upper, and mechanism for moving the inserting means around the wipers at a uniform height above the overdrawn upper, substantially as described.

69. A lasting machine, having, in combination, wipers for wiping the upper over the shoe bottom, means for inserting fastenings in the overdrawn upper, mechanism for moving the inserting means around the wipers, and a cam for maintaining the inserting means at a uniform height above the overdrawn upper during its traveling movement, substantially as described.

70. A lasting machine, having, in combination, wipers for wiping the upper over the shoe bottom, means for inserting fastenings in the overdrawn upper, mechanism for moving the inserting means around the wipers, and an adjustable cam for maintaining the inserting means at a uniform height above the overdrawn upper during its traveling movement, substantially as described.

71. A lasting machine, having, in combination, wipers for wiping the upper over the shoe bottom, means for inserting fastenings in the overdrawn upper, mechanism 5 for moving the inserting means around the wipers, and a cam automatically adjusted to the position of the wipers in their overdrawn movement for maintaining the inserting means at a uniform height above the 10 overdrawn upper during its traveling movement, substantially as described.

72. A lasting machine, having, in combination, wipers for wiping the upper over the heel seat, a pair of handles for closing 15 the wipers on the shoe, means for inserting fastenings including a height gage, a cam coöperating with the height gage for controlling the height at which the inserting means operates above the work, and connections 20 between the handles and the cam for adjusting the cam to the slope of the work, substantially as described.

73. A lasting machine, having, in combination, wipers for wiping the upper over 25 the heel seat, means for inserting fastenings including a height gage, a cam coöperating with the height gage for controlling the height at which the inserting means oper-

ates above the work, and connections between the wipers and the cam for adjusting the cam to the slope of the work, substantially as described. 30

74. A shoe machine, having, in combination, a work supporting table, operating means including a downhold, a clamping device for clamping the work on the table, and a single means for actuating the downhold and clamping device to engage the work, substantially as described. 35

75. A shoe machine, having, in combination, a work supporting table, a jack having runners thereon mounted to slide on the table into operative position, operating means including a downhold, a clamping device for clamping the runners to the table, and a single means for actuating the downhold to engage the work and the clamping device to clamp the runners, substantially as described. 40

76. A shoe machine, having, in combination, a shoe support; a guide engaged with the shoe; operating means including a gage; means for pressing the gage yieldingly against the guide; and means for moving the gage along the guide, substantially as described. 45

CHARLES C. BLAKE.
